UNITED STATES PATENT OFFICE.

SEVER P. KILLY, OF KANSAS CITY, MISSOURI, ASSIGNOR TO JOHN O. LYTLE AND
CHARLES G. EDGERTON, OF SUGAR CITY, COLORADO.

CLEANING COMPOSITION.

No Drawing.

Application filed June 22, 1920. Serial No. 390,791.

To all whom it may concern:

Be it known that I, SEVER P. KILLY, a citizen of the United States, residing at Kansas City, in the county of Jackson and State of Missouri, have invented certain new and useful Improvements in Cleaning Compositions, of which the following is a specification.

This invention relates to cleaning compositions and has for its general object to provide a cleaning composition which will be highly effective in removing grease, dirt, and stains from ink, iodine, paint, shellac, dye, etc. without any likelihood whatsoever of injury to the hands or any material or surface being cleaned.

Another object of the invention is to provide a composition for the purpose stated which will not be injurious to the skin but which will on the other hand heal and soothe cuts and abrasions and will leave the skin in a soft and pliable condition.

A further object of the invention is to provide a cleaning composition which may be employed on the person as well as in cleaning carpets, furniture, floors, and in fact all metal or wood surfaces and which when employed in cleaning polished surfaces, will not in any way injuriously affect the polish but will on the other hand impart a lustre to such surfaces.

A further object of the invention is to provide a cleaning composition which will not deteriorate with age, which will not be affected by climatic conditions, which will be non-inflammable, free from acids and injurious alkalies, and which will on the whole be admirably adapted for universal use and be most effective in its action.

The composition embodying the invention consists of a mixture of the following ingredients in about the proportions stated although it is to be distinctly understood that I am not by any means to be limited

to the proportions mentioned but may vary these proportions if occasion arises.

Sawdust, medium fine 1 gallon.

Or a weight of $3\frac{1}{2}$ to 5 pounds
depending on the kind of
wood used.

Crude paraffine oil 24 ounces.

Borax 2 "

Sal soda 6 "

Ivory or other soap chips 6 "

Soft water 32 " 55

Oil of lavender 2 drachms.

In preparing the composition I first suitably pulverize and sift the sawdust so as to obtain the same in a uniform condition, and then thoroughly dry this ingredient. The sawdust is then mixed with the oils recited above and during the mixing operation will absorb these oils. I next add the borax, sal soda, and soap chips to the quantity of water stated and heat this mixture until all of the ingredients are thoroughly dissolved in the water. I then mix this solution with the oil impregnated sawdust prepared in accordance with the first step described above, and in this manner the finished composition is prepared for use.

The composition is of a pasty nature, all of the liquid ingredients being absorbed by the particles of sawdust, and in the use of the composition a suitable quantity thereof is rubbed on the hands or on any surface which is to be cleaned either with or without the addition of water as may be desired. The hands, or any surface to which the composition has been applied, may then be rinsed or washed with clear water to remove all traces of the composition.

The sawdust employed of course forms the body of the composition and also constitutes a medium for absorbing the liquid ingredients. Also it serves as a polishing medium but at the same time will not in-

jure any surface to which it is applied. The crude paraffine oil keeps the composition in what is claimed as new is: a moist condition, softens the skin when the composition is used on the person, and imparts lustre to highly polished surfaces. The borax softens the water and acts to an extent as an antiseptic, and the sal soda disintegrates the foreign matter or dirt to be removed and is assisted by the soap chips. Of course any perfuming medium may be employed other than oil of lavender.

Having thus described the invention, A cleaning composition having healing properties comprising the following ingredients in about the proportions of sawdust one gallon impregnated with paraffin oil twenty-four ounces, and a solution in water thirty-two ounces of borax two ounces, sal soda six ounces, and soap chips six ounces.

In testimony whereof I affix my signature.

SEVER P. KILLY. [L. S.]
